GRADER

Harvey G. Mosher, Inkster, Mich.

Application November 10, 1941, Serial No. 418,605

4 Claims. (Cl. 37—144)

The invention relates to graders of that type intended for heavy duty and sometimes known as "bulldozers." Such machines are usually provided with an endless chain or so-called caterpillar tread, for advancing the same, and carry at the front end a heavy blade for cutting and shoving forward the ground to be removed. It sometimes happens that an obstacle in the path of the machine is too large or too securely anchored to be displaced by the blade, so that it is necessary to stop operation of the machine until such obstruction is removed.

It is the object of the invention to provide the grader with means for quickly disengaging and removing such obstructions and to also adapt the machine for other work. To this end the invention consists:

First, in providing the grader with a forwardly extending boom and hoist, which is operable by mechanism and controls on the machine; and

Second, in the novel construction as hereinafter set forth.

In the drawing:

Fig. 1 is a side elevation of my improved grader;

Fig. 2 is a plan view thereof.

The grader to which my improvements are applied is of standard construction and forms no part of the present invention. Briefly described, it comprises a tractor A provided with a cab B for the operator and the controls, and endless chain or caterpillar tread drivers C on opposite sides thereof. The blade D is carried by a U-shaped frame E embracing the tractor and pivotally connected thereto at its rear end, said frame being raised and lowered by suitable hydraulic mechanism which, as shown, comprises the cylinder F, bell crank lever F', and link F". The blade D is preferably centrally pivoted to the frame E and is provided at its opposite ends with adjustable links E' through which the angle of the blade may be changed as desired.

My improvement comprises a boom G having the bifurcated rear end portion G' pivotally attached at H to the U-shaped frame E. The boom, preferably a hollow box member, extends forward over the blade D in the central plane of the machine and is supported at the desired angle and raised or lowered by a guy cable I. One end of this is fixedly attached to one side of the frame E, passing forward therefrom and around a sheave J near the forward end of the boom and then rearward to the opposite side of the frame E where it is attached to a winding drum K. This drum may be operated by a suitable

crank-actuated mechanism to adjust the boom to the desired angle. At the forward end of the boom is a sheave L for a hoisting cable M provided at its outer end with a suitable hook N. The rear end portion of the cable is wound upon a drum O having a hand-operated crank O' and suitable ratchet or holding means O". Intermediate this drum and the sheave L there is mounted, preferably within the hollow boom, a hydraulic jack P, the plunger of which carries a sheave Q for engaging the cable M. The arrangement is such that when the plunger of the jack is moved rearward, it will draw a loop in the cable M, thereby lifting the hook N to raise a load suspended thereby.

With the construction as described, the grader is operated in the usual manner, the boom G being raised to a sufficient angle to be out of the way. If an obstruction is in the path of the blade D, the hook N on the cable M is lowered by unwinding the portion of the cable on the drum O, and the hook is then suitably connected with the obstructing member. The slack in the cable is taken up by winding up the drum O, after which the hydraulic jack P is operated to move rearward the sheave Q, drawing a loop in the cable, as indicated in dotted lines in Fig. 1. This will lift the obstructing member, which can then be carried by the tractor to a suitable point for deposit. If the amount of movement effected by the hydraulic jack P is not sufficient to lift the obstructing member clear of the ground, the hydraulic cylinder F, connected with the frame E, may be operated to effect a further lifting.

My improvement also adapts the grader for the performance of other useful operations. Thus, one of the uses of the machine is for the refilling of trenches in which pipe or tile have been laid. With my improved construction, the hoist is useful in the handling of such pipe or tile, as well as for the performance of its usual function.

While I have described the boom as being mounted on the frame which carries the blade, it is obvious that it might be mounted on the blade itself.

My improved construction greatly facilitates the operation of the grader, for the boom is always in position, ready for instantaneous use, and the hoisting apparatus may also be quickly operated.

While I have described a specific construction, it is obvious that the structure, both of the boom and the hoisting apparatus, may be varied without departing from the spirit of my invention.

What I claim as my invention is:

1. In a grader, the combination with a tractor, a blade propelled thereby located forward thereof, and a frame on which said blade is mounted vertically adjustable in relation to said tractor, of a boom mounted on said frame and extending forward over said blade, a cable hoist depending from the forward end of said boom, and hydraulic-actuated means for operating said hoist.

2. In a grader, the combination with a tractor, a blade propelled thereby located forward thereof, and a frame on which said blade is mounted provided with hydraulic operating mechanism for raising or lowering the same, of a boom having its rear end mounted on said frame and extending forward over said blade, cable guy means for raising and holding said boom at a desired angle, a cable hoist depending from the forward end of said boom, and a hydraulic jack mounted on said boom for actuating said hoist.

3. In a grader, the combination with a tractor, a blade propelled thereby located forward thereof, and a frame on which said blade is mounted provided with hydraulic operating mechanism for raising or lowering the same, of

5 a hollow boom having its rear end mounted on said frame and extending forward over said blade, cable guy means for raising and holding said boom at a desired angle, a cable hoist depending from the forward end of said boom, and a hydraulic jack mounted within said hollow boom for actuating said hoist.

10 4. In a grader, the combination with a tractor, a blade propelled thereby located forward thereof, and a frame on which said blade is mounted provided with hydraulic operating mechanism for raising or lowering the same, of a boom having its rear end mounted on said frame and extending forward over said blade, means for raising and holding said boom at a desired angle, a cable hoist depending from the forward end of said boom passing around a sheave at said forward end, a winding drum mounted on the boom to which the opposite end of said cable is attached,

15 20 a hydraulic jack mounted on the boom, and a sheave actuated by said jack engaging said cable between its depending portion and said winding drum being adapted to draw a loop in said cable and to thereby raise its depending portion.

HARVEY G. MOSHER.
